URINAL DEVICE

William J. Butcher, Jamaica, N. Y.

Application March 10, 1949, Serial No. 80,590

6 Claims. (Cl. 4—119)

1

This invention relates to urinal devices and has to do particularly with such devices intended for male use in conjunction with the use of a bed pan.

The use of a bed pan by a male is awkward and uncomfortable inasmuch as it is difficult for the male to place the buttocks properly on the pan while at the same time urinating comfortably without soiling. Furthermore, the taking of an uncontaminated specimen from a patient by employing a bed pan for doing so is a rather unsatisfactory proceeding. The device of the invention furnishes a solution to these problems which have persisted in the prior art and does so in a simple, economical manner.

It is, accordingly an object of this invention to provide a male urinal device for use with a bed pan.

Another object of the invention is to provide such a device which may be mounted to discharge either into the bed pan or outside of it for the collection of a specimen.

Still another object is to provide such a device which is readily demountable and reversible.

Further objects are to provide such a device which is simple, easy to use, easy to clean, and fully effective for the intended purpose.

Further and more detailed objects of the invention will become apparent from the following description of the invention taken in conjunction with the accompanying drawing in which

Figure 1 is a front elevation of the device of the invention as viewed in operative position;

Figure 2 is a side elevation thereof looking at Figure 1 from the left side thereof.

Figure 3 is a vertical section taken on line 3—3 of Figure 1 and looking in the direction of the arrows;

Figure 4 is a view of the device as in Figure 2 but showing it in reduced scale and as applied to a bed pan to discharge into the pan, and

Figure 5 is a view similar to Figure 4 but with the device mounted in reversed position for the collection of a specimen.

The urinal device of the invention is constructed to be used with a bed pan either for the discharge of urine into the bed pan or the collection of a specimen outside of the bed pan. The device consists of a funnel type urinal member, shown generally at 1 and a mounting member therefor shown generally at 2. The member 1 may be made of any suitable material among which I have found stainless steel and a variety of the available plastics to be satisfac-

2

tory. Stainless steel is preferable due to the ease with which it may be cleaned and sterilized.

The body of the member 1 has its upper portion formed as a section of a curved cone, or horn, 3, increasing in size as it extends upward and inward to its mouth 4. The mouth 4 and adjacent portion of the member 1 is sufficiently large to receive the end of the male organ so that urination can be effected right down into the desired receptacle without any loss or splattering.

The lower portion of the member 1 preferably departs from the curved conical shape of the major, upper portion. Thus, from the position 5 to its lower end 6 the member 1 is of cylindrical shape. The portion so shaped is indicated at 7. Such cylindrical shaping facilitates the mounting of the member for use as will now be explained.

20 The mounting member, generally indicated at 2, is provided with a receiving element 8 whose upper part is formed as a cylinder. This cylinder is of proper internal diameter to slidably receive and rotatably mount the portion 7 of the member 1. Thus, the member 1 may be applied to the element 8, rotated to desired position when mounted therein, or removed therefrom with ease.

25 The lower section of the receiving element 8 is curved from the position 9 to the lower end 10 in a direction away from the holding or mounting plate 11 which forms the other principal part of the member 2. The plate 11 is substantially wider than the portion 8 but is generally the same height as the same and extends in spaced relation thereto. At its top the plate 11 is formed with a bridging portion or member 12 engaged with the top of the portion 8 at 13. This engagement may be of any suitable secure form or both the plate and the element 8 may be parts of an integral construction.

30 By spacing the plate 11 from the receiving element 8, and making the plate 11 of substantial extent, the mounting member is adapted to seat on the edge of a bed pan 14, as indicated in Figures 4 and 5. The common bed pan would have a bottom 15, and a relatively straight side wall 16 at one end thereof, while the wall 16 would probably terminate at its upper edge in a finished portion such as the bead 17. Thus, the mounting member 2 could readily seat on the wall 16 with the element 8 on one side thereof and the plate 11 on the other side thereof. A light clamping of the wall 16 between the element 8 and the plate 11 may be effected if de-

sired, though if the plate 11 were of proper size and weight its counterbalancing effect would normally be sufficient to properly mount the member 2 on the edge of the bed pan.

In Figure 4 the complete urinal device is shown mounted in position for urine to discharge into the bed pan. The curved cone 1 is directed inwardly and the element 8 lies inside the pan while the plate 11 lies outside of the wall 16. In the Figure 5 showing, the mounting member 2 is reversed with the element 8 lying outside of the bed pan. Here the outward curve of the lower part of element 8 is advantageous. It affords room for the seating of a suitable container, such as the bottle 18 under the end 10 in order to catch a specimen. Here also the cone 1 has been turned at 180° from its position in Figure 4, so that the mouth 10 is presented in operative position. It is well to point out here that there should be a moderate drag, or resistance, to the turning of the cone 1, so that it will not turn inadvertently and thus fail to function as intended.

While a cylindrical bearing relationship has been indicated as preferable between the portion 7 and the element 8, it is of course to be understood that the taper of the cone 1 might be continued right down to the end 6. In the latter case, the element 8 would be similarly tapered. As shown in Figure 3, the portion 7 of the cone 1 only extends into the element 8 to a position just above the commencement of the curve 9. Further penetration is prevented by the increase in diameter of the member 1, as it departs from the cylindrical shape and commences its conical flare at the position 5. Should the member 1 be made of a suitable plastic, an outwardly extending bead could easily be formed around the member 1, at the position 5. This would be more desirable for a plastic construction than the stainless steel one where there is no need for it.

It will be apparent from the foregoing that the device of my invention meets a definite need in the male use of a bed pan. The device can be quickly applied to normal bed pans, it can be similarly removed therefrom and it can be readily taken apart for cleaning and sterilizing. It can be easily handled and manipulated and can be stowed away inside of the bed pan or in some small space elsewhere.

While I have shown and described what is presently considered as the preferred form of embodiment of the invention, it is to be understood that the invention is susceptible of variations therefrom and other embodiments thereof without departing from the spirit and scope of the invention as defined in the appended claims.

Having described my invention, what I claim as new and desire to secure by Letters Patent is:

1. A device for receiving a urinal member and supporting the same on a wall of a bed pan which comprises an open ended elongated tubular receiving element adapted to engage one side of the wall of a bed pan, a mounting plate of substantially the same length as said tubular receiving element, and of a width substantially the same as its length, said plate extending in substantially the same direction as said tubular receiving element and in spaced relation thereto and being adapted to engage the other side of said bed pan wall, the lower portion of said tubular receiving element being curved away from said mounting plate and a bridging member extending between and secured to the upper end of said tubular element and the upper end of said mount-

ing plate, said bridging member being adapted to lie across the upper edge of said bed pan wall and secure said tubular element and said mounting plate in said spaced relationship.

5. 2. A device of the character described comprising a urinal member and a mounting member for mounting the same on a bed pan, said urinal member including an extending portion and a mounting portion, said extending portion formed 10 as a section of an upwardly enlarging laterally curving cone and said mounting portion extending straight downwardly from the lower end of said cone, said mounting member including an open ended substantially cylindrical elongated receiving element with an internal diameter substantially the same as the external diameter of said mounting portion of said urinal member, a wide, elongated mounting plate lying alongside of and in spaced relation with respect to said 15 cylindrical receiving element and a bridging member engaging the upper ends of said cylindrical elongated element and said mounting plate and adapted to lie across the top edge of a wall of a bed pan with said cylindrical elongated element and said mounting plate extending down one on either side of said bed pan wall and in engagement therewith, said urinal member being mounted on said mounting member with the mounting portion of said urinal member received 20 within said cylindrical elongated element.

3. A device of the character described comprising a urinal member and a mounting member for mounting the same on a bed pan, said urinal member including an extending portion and a mounting portion, said extending portion formed as a section of an upwardly enlarging laterally curving cone and said mounting portion extending straight downwardly in the form of a cylinder from the lower end of said cone, said 35 mounting member including an open ended substantially cylindrical elongated element having a straight upper portion with an internal diameter substantially the same as the external diameter of said mounting portion of said urinal member, said cylindrical elongated element being adapted to lie against one face of the wall of a bed pan, and a wide elongated mounting plate lying alongside of and in spaced relation with respect to said cylindrical elongated member and being adapted to lie against the other face of said bed pan wall and a bridging element connecting the upper end of said elongated mounting plate with the upper end of said cylindrical elongated element to maintain said element and 40 said member in spaced relation and to lie across the upper edge of said bed pan wall, said urinal member being mounted on said mounting member with the mounting portion thereof received within said cylindrical elongated element.

6. 4. A device of the character described comprising a urinal member and a mounting member for mounting the same on a bed pan, said urinal member comprising an upwardly opening, laterally curved cone terminating at its upper end in 45 a sidewise-opening, enlarged mouth, the lower end of said cone formed into a downwardly extending mounting portion, said mounting member including an open ended elongated cylindrical receiving element and an elongated wide plate 50 like member lying side by side in spaced relation to receive the wall of a bed pan therebetween and to engage the opposite sides thereof, and a bridging member secured to the upper ends of said cylindrical receiving member and said plate like member to secure the same together in said

spaced relation and to overlie the upper edge of said bed pan wall, said cylindrical receiving element having its upper portion formed to snugly receive said mounting portion of said urinal member and having its lower portion curved away from said plate like member to direct liquid away from said bed pan wall, said urinal member being mounted on said mounting member with the mounting portion thereof seated within said cylindrical receiving element.

5. A device for receiving a urinal member and supporting the same on a wall of a bed pan which comprises, an open-ended elongated tubular receiving element, said receiving element having an upper entrant portion and a lower discharging portion, said entrant portion being adapted to engage one side of the wall of a bed pan and said discharging portion being adapted to extend away from said wall, a wide, elongated mounting plate lying alongside of and in spaced relation with respect to said receiving element and being adapted to engage the other side of said bed pan wall, said discharge portion being formed to curve away from said mounting plate, and a bridging member extending between and secured to the upper end of said tubular receiving element and to the upper end of said mounting plate, said bridging member being adapted to lie across the upper edge of said bed pan wall and secure said tubular element and said mounting plate in spaced relationship.

6. A device for receiving a urinal member and supporting the same on a wall of a bed pan which comprises, an open ended elongated tubular receiving element, said receiving element having an upper entrant portion extending throughout

the greater part of the length of said receiving element and having a short lower discharging portion, said entrant portion being adapted to engage one side of the wall of a bed pan and said discharging portion being adapted to extend away from said wall, an elongated mounting plate lying alongside of and in spaced relation with respect to said receiving element and being adapted to engage the other side of said bed pan wall, 5 said discharging portion being formed to curve away from said mounting plate, and a bridging member extending between and secured to the upper end of said tubular receiving element on to the upper end of said mounting plate, said bridging member being adapted to lie across the upper edge of said bed pan wall and secure said tubular element and said mounting plate in said spaced relationship.
